UNITED STATES PATENT OFFICE.

CLARENCE W. BRIDGES, OF SAN FRANCISCO, CALIFORNIA.

DESIGN FOR A WATCH OR CLOCK DIAL.

45,101.

Specification for Design.

Patented Jan. 6, 1914.

Application filed May 3, 1913. Serial No. 765,335. Term of patent 14 years.

To all whom it may concern:

Be it known that I, CLARENCE W. BRIDGES, a citizen of the United States, residing in the city and county of San Francisco, State of California, have invented a new, original, and ornamental Design for a Watch or Clock Dial, of which the following is a specification, reference being had to the accompanying drawings, forming part thereof, wherein the figure is a view in elevation of a dial, showing my new design.

I claim:

The ornamental design for a watch or clock dial as shown.

In witness whereof I have signed my name to this specification in the presence of two witnesses.

CLARENCE W. BRIDGES.

Witnesses:

HARRY A. TOTTEN,
D. B. RICHARDS.
